UNITED STATES PATENT OFFICE.

CHARLES J. TAGLIABUE, OF BROOKLYN, NEW YORK, ASSIGNOR TO C. J. TAGLIABUE
MANUFACTURING COMPANY, A CORPORATION OF NEW YORK.

OIL-TESTER.

1,263,145.

Specification of Letters Patent. Patented Apr. 16, 1918.

Application filed August 14, 1915. Serial No. 45,465.

To all whom it may concern:

Be it known that I, CHARLES J. TAGLIABUE, a citizen of the United States, and resident of Brooklyn, county of Kings, and State of New York, have invented certain new and useful Improvements in Oil-Testers, of which the following is a specification.

My invention relates primarily to open testers for testing the flash point and the point at which the oil will take fire. Open testers of this type are usually provided with a wire rest across the top of the oil cup over which a burner tip provided with a small ignition flame is adapted to be drawn in order to ascertain the flash point of the oil being tested. It has been found that with testers of this kind errors may arise, because different experimenters or even the same experimenter at different times can not be expected to pass the testing flame over the oil every time at the same distance above the surface of the oil.

The object of my improvement is to provide the oil tester with a gas burner adapted to be permanently supported at a fixed distance above the oil cup so that it may be swung across the top thereof in a horizontal plane thus insuring like conditions for all tests. I have also provided means for regulating the size of the flame and a suitable gage with which to compare the flame in order that a standard size for the flame may be maintained during the various or repeated tests that may be made.

I have illustrated one adaptation of my improved device in the accompanying drawings in which Figure 1 represents a side elevation of an open tester of the usual form and Fig. 2 is a top plan view thereof.

Referring to the drawings 1 represents the base of the tester which is adapted to support a waterbath 2 in which an oil cup 3 is adapted to dip substantially as indicated by the dotted lines in Fig. 1. One side 45 of the bath is preferably provided with a binding post or stud 4 and a wire runner 5 through which a supporting rod or wire 6 is adapted to pass, the lower end of the wire being clamped by means of an adjusting screw 7. The upper end of the wire 6 is bent over the oil cup 3 and is provided with a hook at 8 from which a thermometer 9 is suspended, the lower end of the thermometer being adapted to enter the oil in the oil cup

3 and give the temperature thereof while 55 making the test.

At one side of the bath 2, I preferably secure a bracket or support 10 having a tubular bearing 11 secured thereto and extending in a vertical direction substantially parallel with the axis of the bath. A gas tube 12 is rotatably mounted in the bearing 11, the upper end being enlarged at 13 so as to provide a shoulder resting upon the tubular bearing 11 at 14 to support the same 65 in a fixed position. The upper end of the gas tube is preferably extended by an elbow joint at 15, one arm of which extends horizontally or substantially at right angles to the tube 12 and is provided with a burner 70 tip at 16 where a small testing flame 17 is adapted to be produced. The elbow 15 is preferably threaded at 16 and screwed into the upper end of the enlarged tubular portion 13 of the gas tube 12. This threaded 75 connection at 16 between the burner and the gas tube enables one to adjust the position of the burner tip above the surface of the oil in the cup when so desired. In making the test for the flash point of the oil under 80 consideration it is necessary to swing the burner 16, with its small flame tip, horizontally across the top of the oil cup 3 from time to time, taking the temperature each time by reading the thermometer. In order 85 to swing the burner horizontally over the oil cup I preferably provide the gas tube 12 with a short horizontally projecting handle 18 which is preferably connected with the tube through a slot 19 in the tubular bearing 11, the end walls of the slot being adapted to limit the turning movement of the tube and burner to about 180° as indicated in Fig. 2 of the drawing. It will be understood, however, that other suitable means 90 for swinging the burner horizontally and for limiting its movement, may be employed. In order to insure uniformity of the tests it is necessary that the flame tip be of a constant or uniform size and in order to 100 gage the size thereof I provide the outer end of the arm 18 with a small sphere 20 adapted to indicate to the eye of the observer the size to which the flame tip 17 should be adjusted. In order that this adjustment may be readily made the lower end of the gas tube 12 is preferably provided with a stop cock 21 which may be readily

turned to vary the flow of gas, and hence controls the size of the gas flame at 17. The lower end of the stop cock member 21 at 22 is provided with a nipple for attaching thereto a rubber tube 23 which may be connected with a source of gas supplied in the usual or any preferred manner. The bath 2 is heated in the usual manner by an alcohol lamp 24 or other suitable means as 10 may be required or desired.

It will be understood that various modifications in the specific details of my improvement may be made without departing from the spirit and scope of the invention.

15 I claim:

1. In an open tester for oils the combination with a water bath having an open oil cup therein, of a bracket support on said water bath and a gas tube rotatably mounted 20 in said bracket support, said tube being provided with a burner tip adapted to be swung in a horizontal plane over said oil cup.

2. In an open tester for oils the combination with a water bath having an open oil 25 cup therein, of a bracket support on said water bath, a gas tube rotatably mounted in said bracket support, and means co-acting between the burner tube and said bracket to limit the rotary movement of said tube in 30 either direction, said tube being provided with a burner tip adapted to be swung in a horizontal plane over said oil cup.

3. In an open tester for oils the combination with a water bath having an open oil 35 cup therein, of a bracket support on said water bath, a gas tube rotatably mounted in said bracket support, a burner tip connected with said tube, and means for turning said tube to swing said burner tip over said oil 40 cup in a horizontal plane.

4. In an open tester for oils the combination with a water bath having an oil cup 45 therein, of a bracket secured to the side of said bath, a vertically disposed tubular bearing on said bracket, a gas tube rotatably mounted in said bearing, a burner tip projecting horizontally from said tube adapted to clear the top of said cup means for maintaining said burner tip at a predetermined 50 fixed distance above said cup and means

for rotating said tube to swing the burner tip horizontally across the top of said cup.

5. In an open tester for oils the combination with a water bath having an oil cup therein, of a bracket secured to the side of 55 said bath, a vertically disposed tubular bearing on said bracket, a gas tube rotatably mounted in said bearing, a burner tip projecting horizontally from said tube adapted to clear the top of said cup means for maintaining said burner tip at a predetermined fixed distance above said cup, a stop cock in said tube for regulating the size of the flame at the burner tip and means for rotating said tube to swing the burner tip horizontally across the top of said cup. 60

6. In an open tester for oils the combination with a water bath having an oil cup therein, of a gas tube vertically disposed along the side of said bath, means projecting from the side of the bath for rotatably supporting said tube, a burner tip extending horizontally from the upper end of said tube and adapted to be swung across the top of 70 said cup a finger lever connected with said tube for rotating the same, said lever being provided with a knob adapted to serve as a gage for the size of the flame at the burner tip and a stop cock in said tube for adjusting the size of the flame. 75

7. In an oil tester, a water bath having an open oil cup therein, a burner tip adapted to be moved across and above said oil cup, means confining said movement to a definite horizontal plane, a lever connected with the 85 burner tip for manipulating said tip said lever having a knob adapted to serve as a gage for the size of the flame, and means for adjusting the size of the flame.

8. In an oil tester, a water bath having an open oil cup therein, a burner tip adapted to be moved across and above said oil cup, means confining said movement to a definite horizontal plane, a knob adjacent to the burner tip to serve as a gage for the size of 90 the flame, and means for adjusting the size of the flame. 95

In testimony whereof I have hereunto set my hand.

CHARLES J. TAGLIABUE.
